INTERLOCKED SASH CONSTRUCTION
Waldo O. Johnson, Wooster, Ohio, assignor to Weather-
Seal, Inc., County of Summit, Ohio, a corporation of
Ohio

Filed Aug. 12, 1960, Ser. No. 49,199
4 Claims. (Cl. 20—56)

The present invention relates to a novel window sash construction or assembly and especially to a novel and improved window sash having an improved interlocked corner construction and where the window sash is made from metal sash rails of extruded shape in section.

Heretofore there have been various types of window sash constructions proposed where the sash is made from metal sash rails. In all of such different window sashes, it always has been a problem to form the sashes of a sturdy, rigid construction and where the sash components can be conveniently and readily assembled with a minimum amount of assembly time and labor but yet with the provision of a desired sturdy, rigid window sash unit.

The general object of the present invention is to provide an improved window sash construction characterized by the provision of readily interlocked corners in the window sash.

Another object of the invention is to provide a window sash made from a plurality of extruded metal shapes and where special slots are formed in the legs of one pair of opposed sash members and with the other opposed pair of sash members having recesses provided in the ends thereof whereby an interlocked engagement can be formed between the slotted ends on one pair of sash members with the recessed parts on the other pair of sash members.

Another object of the invention is to provide top and bottom rails in a window sash that are thicker than the side sash rails whereby the side sash rails can be slid into engagement with the top and bottom rails and have slotted portions provided in the side sash rails for engaging edge flanges formed on the top and bottom rails but with the edge flanges terminating spaced from the ends of the top and bottom rails.

Further objects of the invention are to form a window sash assembly from a plurality of extruded metal shapes having a minimum of machining or shaping operations provided thereon but by which interlocked corner units can be formed in the window sash, to form a window sash the components of which can be conveniently and relatively assembled to form a sturdy, improved window sash unit, to abut side sash rails in a window sash against inner base sections of top and bottom rails in the window sash for forming a rigid interlocked sash unit, and to retain the window sash components together by a window pane and a plastic sealing strip for the window pane that frictionally engages the sash components.

The foregoing and other objects and advantages of the invention will be made more apparent as the specification proceeds.

Attention now is particularly directed to the accompanying drawings wherein one currently preferred embodiment of the principles of the invention is shown, and wherein:

FIG. 1 is an elevation of a pair of window sashes of the invention;

FIGS. 2 and 3 are enlarged sections taken on lines 2—2 and 3—3 of FIG. 1, respectively;

FIG. 4 is an exploded view of a side sash rail and bottom sash meeting rail of the invention;

FIG. 5 is a top plan of the bottom sash meeting rail of the sash unit of the invention;

2

FIG. 6 is an enlarged section of the interlocked lower corner of the sash of FIG. 1;

FIG. 7 is a vertical section taken on line 7—7 of FIG. 1 with the window pane and securing strip removed;

FIG. 8 is an exploded elevation of the rails of the corner shown in FIG. 6; and

FIG. 9 is a top plan of the bottom rail of the lower sash.

When referring to corresponding members shown in the drawings and referred to in the specification, corresponding numerals are used to facilitate comparison therebetween.

Generally speaking, the present invention relates to a window sash comprising a pair of side sash rails which may be of generally H-shaped in horizontal section to form base sections in the rails with pairs of parallel inner legs and outer legs extending therefrom, a meeting rail usually of generally U-shape in vertical section, and a bottom rail of generally U-shape in vertical section. The meeting rail and bottom rail are thicker than the side sash rails and include base sections and pairs of parallel legs with inwardly extending edge flanges thereon extending from the base sections, the edge flanges being omitted, or removed, at the ends of the said meeting and bottom rails, and the side rails, meeting rail and bottom rail have interlocking corner connections formed therebetween by slotting the inner legs and positioning the side sash rails within the meeting and bottom rails to engage the slots with the edge flanges.

With particular reference now to the details of the structure shown in the drawings, window sashes of the invention are indicated as a whole by the numerals 1 and 1a. The sash 1 is made from a pair of side rails

2 and 3, which, as best shown in FIG. 2, comprise members which may be of substantially H-shape in horizontal section to form base sections 4 in the side rails with pairs of parallel inwardly extending legs 5 and 6 thereon and with pairs of parallel legs 7, 8 extending in the opposite direction from the base sections 4. The sash as shown also includes, along the top, a meeting rail 9 which has a base section 10 provided therein with a pair of parallel legs 11 and 12 extending inwardly of the sash from such base section 10. The meeting rail

9 also has a laterally projecting sash meeting flange 13 provided thereon for engaging a similar flange provided on the upper sash 1a normally associated with the sash 1 for forming a pair of slidably associated or double hung sashes, as used in most window assemblies. The parallel legs 11 and 12 also each have formed integrally therewith one of a pair of inwardly extending edge flanges 14 and 15, as best shown in FIG. 3.

Usually a bottom rail 16 in the sash 1 is of similar construction to the meeting rail 9 and has a base section 17 formed therein with a pair of parallel legs 18 and 19 extending therefrom. These legs 18 and 19 also have edge flanges 20 and 21 formed thereon in opposed relationship to each other and extending inwardly of the bottom rail 16 towards each other for a purpose to be hereinafter described in more detail.

In order to obtain the desired interlocked corner construction by use of the sash rail means of the invention, in this instance, a pair of parallel slots 22 and 23 are formed in the inner legs 6 and 5 of each of the side rails 2 and 3 adjacent each end thereof. Normally these

slots 22 and 23 extend the length of such inner legs 6 and 5 down to the base sections 4 formed in the side rails. Provision is made for receiving the slots 22 and 23 and the side rails in interlocking engagement with the meeting rail and bottom rail by removing, in some suitable manner as by milling, the edge flanges 14 and 15 and 20 and 21 and part of the bases provided on the meeting rail 9 and bottom rail 16, respectively, at each end of

such rails. FIGS. 5 and 9 of the drawings best show how recesses 24 and 25 are formed in each end of the meeting rail 9 and bottom rail 16, respectively, and with such recesses 24 and 25 extending axially of the respective rails a distance equal to the combined depth of the base sections 4 of the side rails plus the length of the outer legs 7 and 8 of the side rails. Of course, the meeting rails and the top or bottom rails can be made in other manners and have the recesses 24 and 25 of the base sections and edge flanges provided therein in any suitable manner. Likewise, the slots 22 and 23 formed in the side rails are positioned at a distance axially of the side rails equal to the distance of the edge flanges 14 and 15, and 20 and 21 from the base sections formed in the meeting rails and bottom rails of the sash of the invention. The slots 22 and 23 are at least of the size of the vertical length of the edge flanges 14 and 15, and 20 and 21, so that the slots 22 and 23 can be slid or telescoped into engagement with the edge flanges at the ends of the meeting rail and bottom rail 16. At the same time, the ends of the side rails 2 and 3 can be and are abutted against the base sections 10 and 17 on the rails 9 and 16 to further reinforce the interlocked corner engagement provided.

The window sash 1 of the invention is completed as a further feature of the invention by positioning a window pane 26 in the center portion of the window sash, and this can be done by use of conventional means, such as a plastic strip 27 of generally U-shape in section. The plastic strip 27 is positioned around the edges of the window pane 26 and snugly or frictionally engages the inner legs 5 and 6 on the side rails and also engages the flanges on the legs 11 and 12 and 18 and 19 provided, respectively, on the meeting rail 9 and bottom rail 16, whereby a rigid, readily assembled window sash 1 is provided and it has a window pane positioned therein. The window sash components are thus held in assembled relation by the plastic strip 27 and window pane 26.

From the foregoing, it is believed that a novel and improved type of a window unit has been provided and with the window sash of the invention being formed from extruded metal shapes having a minimum of special forming actions provided thereon. However, the window sash is of excellent physical properties and will give a long service life in use.

It will be realized that the window sashes 1 and 1a can be received in any desired type of window frame means for providing a so-called storm window sash for homes and other buildings.

The sashes may be assembled by engaging the meeting rail 9 and bottom rail 16 with a sealing strip 27 and a window pane 26. Next, the pair of opposed side rails would be telescoped or slid into engagement with the window pane 26 and ends of the rails 9 and 16 to provide the desired sturdy assembly.

The outer legs 7 and 8 formed in the side rails may have a suitable runner or guide means carried thereby, if desired, whereas the base section of the bottom rail 16, may likewise have any desired sealing strip, or other member carried thereby.

Obviously the sash 1 can be made for use as an upper sash 1a, as well as a lower sash in any desired window assembly. Thus in such instance the meeting rail would be at the lower margin of the window sash and with the bottom rail 16 then being of very similar design and forming the upper rail in the window sash. Hence, the terms "upper meeting rail" and "bottom rail" are used only in a relative sense and are not limiting. Likewise, the expression "thickness," or the like, when referring to the rails in the sash is taken as the inner-to-outer measurement of the sash rail. "Thickness" hence, unless otherwise specified, is measured normal to the plane defined by the sash 1.

In view of the above, it is believed that the objects of the invention have been achieved.

While one complete embodiment of the invention has been disclosed herein, it will be appreciated that modification of this particular embodiment of the invention may be resorted to without departing from the scope of the invention as defined in the appended claims.

What is claimed is:

1. In a window sash, a pair of side sash rails of generally H-shape in horizontal section to form base sections with pairs of parallel inner legs and outer legs extending therefrom, meeting rail of generally U-shape in vertical section and having a laterally protruding sash meeting flange thereon, and a bottom rail of generally U-shape in vertical section, said meeting rail and bottom rail including base sections and pairs of parallel legs, with inwardly extending edge flanges thereon, extending from said base sections, the said parallel inner legs of said side sash rails being horizontally slotted for the length thereof adjacent each end of said side sash rails at a distance therefrom equal to that of said edge flanges from said base sections of said meeting and bottom rails and for the vertical length of said edge flanges, said edge flanges terminating at each end of said meeting rail and bottom rail at a distance spaced therefrom equal to the combined depth of one of said side rail base sections and the length of said outer legs on said side rails whereby said side rail slots can be slid into engagement with said edge flanges of said meeting and bottom rails by movement of said side rails parallel to the longitudinal axes of said meeting and bottom rails, and the ends of said side rails abut on the said base sections of said meeting and bottom rails to form solid corners in the window sash.

2. In a window sash, a pair of sash rails of generally H-shape in section to form base sections with pairs of parallel laterally inwardly extending legs and laterally outwardly extending outer legs thereon, a meeting rail of generally U-shape in section, and a fourth rail of generally U-shape in section, said meeting rail and fourth rail being thicker than said side sash rails and including base sections and pairs of parallel legs, with opposed edge flanges thereon, extending from said base sections, said edge flanges terminating at a point spaced from the ends of said meeting and fourth rails, a window pane received in said inwardly extending legs and parallel legs to fill the center of the window sash, and a sealing member aiding in securing said window pane to said rails, said sash rails having slots formed in said inwardly extending legs and extending the length thereof spaced a distance from the ends of said sash rails equal to the length of said parallel legs of said meeting and fourth rails and being of a size to receive said edge flanges, said slots being normal to the longitudinal axis of said sash rails, said side rails, meeting rail and fourth rail having interlocking corners formed therebetween by positioning said side sash rails within said meeting and fourth rails to engage said slots with said edge flanges, the ends of said sash rails abutting against said base sections of said meeting and fourth rails to reinforce the interlocking corners.

3. In a window sash, a pair of equal size sash rails of generally H-shape in section to form base sections with pairs of parallel inner legs and outer legs extending therefrom, a meeting rail of generally U-shape in section, and a fourth rail of generally U-shape in section, said meeting rail and fourth rail being thicker than said side sash rails and including base sections and pairs of parallel legs, with inwardly extending edge flanges thereon, extending from said base sections, said edge flanges terminating at a point spaced from the ends of said meeting and fourth rails a distance equal to the thickness of said sash rail base sections measured in the plane of the sash plus the length of said outer legs of said sash rails, a window pane received in said inner legs and parallel legs to fill the center of the window sash, and a sealing member securing said window pane to said rails to aid in securing said rails together to form the window sash, said

sash rails having rectangular slots formed in said inner legs and extending the length thereof spaced a distance from the ends thereof equal to the length of said parallel legs of said meeting and fourth rails and being of a size to receive said edge flanges snugly, said side rails, meeting rails and fourth rail having interlocking corners formed therebetween by positioning said side sash rails within said meeting and fourth rails to engage said slots with said edge flanges, the ends of said sash rails abutting against said base sections of said meeting and fourth rails 10 to reenforce the interlocking corners, said sash rails being engageable with said meeting and fourth rails by movement parallel to the longitudinal axis of said meeting and fourth rails when said sash rails are positioned adjacent said meeting and fourth rails for engagement therewith.

4. In a window sash, a pair of identical side sash rails of generally H-shape in section to form base sections with pairs of parallel inner legs and outer legs extending therefrom, a meeting rail of generally U-shape in section and having a protruding sash meeting flange thereon, and a fourth rail of generally U-shape in section, said meeting rail and fourth rail including base sections and pairs of parallel legs, with inwardly extending edge flanges thereon, extending from said base sections, said edge flanges terminating at a point spaced from the ends of 20 said meeting and fourth rails, a window member received in said inner legs and parallel legs to fill the center of the window sash, and a sealing member aiding in secur-

15
20
25

ing said window member to said rails, said window and sealing members securing said rails together, said sash rails being thinner than said meeting and fourth rails, said sash rails having slots formed in said inner legs and extending the length thereof normal to the longitudinal axis of said sash rail spaced a distance from the ends thereof equal to the length of said parallel legs of said meeting and fourth rails and being of a size to receive said edge flanges, said side rails, meeting rail and fourth rail having interlocking corners formed therebetween by positioning said side sash rails within said meeting and fourth rails to engage said slots with said edge flanges, the ends of said sash rails abutting against said base sections of said meeting and fourth rails to reenforce the interlocking corners whereby said sash rails can only be separated from said meeting and fourth rails by movement parallel to the longitudinal axes of said meeting and fourth rails.
